UNITED STATES PATENT OFFICE.

GEORGE SIDNEY BOWES, OF NEWCOMERSTOWN, OHIO.

ATTACHMENT FOR RUNNING BOARDS OF AUTOMOBILES.

1,407,514.

Specification of Letters Patent. Patented Feb. 21, 1922.

Application filed September 29 1920. Serial No. 413,532.

To all whom it may concern:

Be it known that I, GEORGE S. BOWES, a citizen of the United States, of Newcomerstown, in the county of Tuscarawas and State 5 of Ohio, have invented certain new and useful Improvements in Attachments for Running Boards of Automobiles; and I do hereby declare the following to be a full, clear, and exact description of the invention, 10 such as will enable others skilled in the art to which it appertains to make and use the same.

This invention relates to improvements in attachments for running-boards of automobiles,—the object of the invention being to provide a tread-plate having a roughened upper face, which may be readily mounted upon the running-board of any automobile, and to provide, as a fixed part of said plate, 20 a scraper which shall be so located with respect to the edge of the plate and the edge of the running-board that the scrapings from the shoe of the user will fall upon the ground.

25 A further object is to so construct a combined tread-plate and scraper for the running-board of an automobile that the scraper shall have such form as to avoid injury to ladies' wearing apparel and also to avoid liability of injurious conflict with the heels of shoes.

With these and other objects in view, the invention consists in certain novel features of construction as hereinafter set forth and 35 pointed out in the claims.

In the accompanying drawing, Figure 1 is a view showing the application of my improvement to the running-board of an automobile, and Figure 2 is a view in section of the device.

40 1 represents the running-board of an automobile on which my improved tread-plate 2 is mounted and secured in any desired manner. The plate 2 is preferably made of metal but might be made of hard rubber or other composition and is provided with a roughened upper face 3 to prevent slipping. The tread-plate 2 is so located on the running-board that one of its edges will be approximately coincident with the free edge 45 of the running-board and is provided with a scraper 4 which projects beyond its edge and also beyond the free edge of the running-board. The scraper 4 is made as a permanent and fixed part of the tread-plate and may be integral therewith, but projects

outwardly from the edge of the tread-plate so that scrapings from foot-wear will drop through the space between the body of said scraper and the edge of the plate. The 60 scraper 4 comprises a body portion 5, the outer face of which will preferably be somewhat curved; end members 6 integral with and at right angles to the body portion 5, and lugs 7 projecting from said end members 65 and disposed over the edge portion of the tread-plate near one end of the latter, said end members being adapted to engage the free edge of the running board and thus insure the proper positioning of the device 70 on the running board. The lugs 7 are made rigid with the tread-plate (preferably integral therewith) and their upper edges and the upper ends of the end members 6 are rounded to prevent possibility of conflict 75 with the apparel of passengers entering or leaving the automobile.

My improvements are applicable to the running-board of any automobile now in use without necessity of recessing or otherwise 80 altering the running-boards for the reception of the same.

Slight changes might be made in the form of the device and the material employed, without departing from the spirit of my 85 invention or limiting its scope and hence I do not wish to restrict myself to the precise details herein set forth.

Having fully described my invention what I claim as new and desire to secure by 90 Letters-Patent is,—

1. An attachment for the running board of a vehicle, comprising a metallic tread plate and a scraper near one end of said plate and spaced from the free edge thereof, 95 said scraper having end members disposed at right angles to the body of the scraper and adapted to abut against the front edge of the running board, and lugs connecting said end members of the scraper with the 100 running board.

2. An attachment for the running board of a vehicle, comprising a metallic tread plate, and a scraper near one end thereof and spaced from the free edge of said plate, 105 said scraper having end members disposed at right angles to the body of the scraper and integral therewith, and rounded lugs integral with and projecting from the upper portions of the end members of the scraper 110 and made rigid with the tread plate.

3. A device of the character described,

comprising a tread-plate, and a scraper, said scraper comprising a body portion spaced from an edge of said plate, end members disposed at right angles to said body member and lugs overlying the tread-plate and rigid therewith, the upper portions of said end members and lugs of the scraper being rounded.

In testimony whereof, I have signed this specification in the presence of two subscribing witnesses.

GEORGE SIDNEY BOWES.

Witnesses:

L. H. WILSON,
SAMUEL ROBINSON.
